ABSTRACT: A centrally apertured radially clamping device for angularly immobilizing an object while allowing lengthwise sliding motion thereof, the device having a hollow enclosed cylindrical body containing a plurality of axially extending flexible filaments encircled by a multiplicity of loose pellets substantially filling the cylindrical body.

PATENTED JUN 15 1971

3,584,453

RADIALLY CLAMPING GRIPS

BACKGROUND OF THE INVENTION

This invention relates to radially clamping grips which exert centripetal forces upon the periphery of a filiform object while permitting movement longitudinally. The objects may be textile yarn, fine gage rods, wire or the like. Grips of this type are disclosed in U.S. Pat. No. 3,372,537 for particular use in the manufacture of yarn from textile fibers in a spinning operation.

In clamping grips of the type described, it is known to have a plurality of flexible filaments fixedly arranged within the body portion to define an enlargeable aperture therethrough. There has generally been a means within the body portion to damp out vibration of the filaments caused by the axial motion of the object being gripped. The known damping means have taken the form of a sleeve-like member positioned around the bundle of filaments and made of a number of resilient materials each having relatively high damping power. In some cases, however, the damping power of such sleeve-like members has been inadequate. In the instant invention damping means for the resilient filaments are disclosed which overcome the disadvantages of the sleeve-like members by the use of a combination of damping forces.

SUMMARY OF THE INVENTION

The clamping grip of this invention permits radial expansion and contraction of the central aperture formed by the bundle of inwardly urged filaments, with vibrations being absorbed by a multiplicity of loose pellets which substantially fill the hollow portion of the grip and are in continuous contact with the flexible filaments.

It is the general object of the invention to devise a radially clamping grip of the type described with damping action provided to the flexible filaments by a damping mass in the form of small spheroids substantially filling the surrounding area.

It is a further object of the invention to obtain increased damping action for the vibrating filaments by the combined forces of a resilient material having high damping power and the frictional restraining force of the spheroids rubbing together.

It is possible with the damping mass of this invention to control the degree of damping action by varying the material which forms the spheroids.

BRIEF DESCRIPTION OF THE DRAWING

The invention will be described by reference to a specific embodiment as illustrated in the accompanying FIGURE of drawing which is a view of the grip in longitudinal section.

DESCRIPTION OF THE PREFERRED EMBODIMENT

Referring to the drawing, the gripping device is formed with a hollow cylindrical body 1, closed at one end by an inlet plug 2 having a funnel-shaped orifice 3 as an inlet for the gripping device. A series of flexible filaments 4a to 4i, etc., is evenly distributed around the axis 5 of the body 1. Each of the flexible filaments is arched at one end so that together they form a bow-net, generally designated 6, positioned around the orifice 3. The other ends of the flexible filaments lie parallel to each other and extend axially to form a bundle, generally designated 7. At the ends which form the flared part of the bow-net, the flexible filaments are anchored in the bottom of a circular recess 8 formed in the inlet plug 2 and the latter has a height such that its base 9 is at the same level as the start of the bundle 7. The base 9 is pierced with a hole 10 which is slightly greater in diameter than the bundle 7, so that when an object is engaged in the grip the bundle 7 is not prevented from expanding radially.

The annular space, bounded by the bundle 7, the inside surface of the cylindrical body 1 and the inlet plug 2, is substantially filled with a multiplicity of pellets 11 which is kept in

place by an outlet plug 12 secured to the lower end of the body 1. Plug 12 is provided with a hole 13 axially aligned with hole 10. The free end of the bundle 7 extends into the hole 13, whose diameter is slightly larger than that of the bundle, to permit radial expansion against the pellets. The hole 13 may be flared outwardly to allow easy discharge of the gripped object.

The pellets 11 together form a damping mass 14 whose damping power is to a large extent due to the pellets rubbing against one another as the bundle 7 is caused to expand and contract.

It is required that the mass 14 have solely a vibration-damping effect, the pellets 11 can be made of a solid material having low deformable properties, such as glass or sand, or of a deformable material having low resilience. If, however, the mass is required to have, in addition to a damping action, a resilient action for boosting the radial gripping force due to the inherent resilience of the flexible filaments forming the bundle 7, pellets made of a readily deformable material can be used. The damping power of the mass 14 would, in this case, be due partly to the pellets 11 rubbing together and partly to the intrinsic damping power of the material of which the pellets were made.

The pellets 11 of the mass 14 should have some yielding property in order for it to give in when the yarn is introduced in the bundle 7 or when the moving yarn has some irregularities. Two cases should be distinguished. If the pellets 11 are made of elastic material, their intrinsic yielding property is sufficient, and the entire annular chamber may be filled. If the pellets 11 are made of solid material, their mass 14 must have some play or clearance. In this latter case, there are two possibilities:

a. One can fill the annular chamber incompletely with the pellets, so as to provide some little free space at the top of this chamber. When the grip rotates, the pellets are indeed submitted to centrifugal forces and the free surface of the mass 14 approaches the form of a paraboloid as would be the case with a liquid. The danger with a very high angular velocity would be that the pellets might rearrange themselves in such a manner that the free space would surround the bundle 7, so that the mass 14 would have no more action on it. But in practice the rearrangement of the pellets under the influence of the centrifugal forces is such that the little free space moves toward the top of the bundle 7, near the hole 10 at the base of the entrance bow-net, so that the pellets maintain their damping action.

b. One can also provide an outer elastic sleeve located between the mass 14 and the inner surface of the body 1. In this embodiment, it is possible to fill the remaining volume entirely up the top of it.

The shape of the pellets should be substantially spherical and conclusive tests have shown satisfactory results with glass spherules of about 0.5 mm. in diameter. With pellets of a solid material it is desirable that the body 1 be of a deformable material to permit the required intermovement of the pellets. In these tests the clamping grip was used in a machine spinning textile yarn and it formed the main component of the twisting member of the machine. The clamping grip rotated around its axis 5 at high speed and the object being gripped consisted of cotton fibers which entered the grip through the funnel 3 where they were gripped and twisted into yarn before issuing from the end of the bundle 7. The twisted yarn, as it was formed, slid continuously along the axis due to the pull applied by a convenient winding member (not shown).

Textile machinery, in particular spinning, doubling and other like machines, is one of the main fields of use for grips of this kind, wherein they form part of the twisting or false-twisting operations provided in such machines. Other uses can be envisaged, but the object being gripped must be an elongated or filiform object which is required to slide lengthwise of the grip while remaining in a fixed angular relationship therewith. For instance, grips of this kind can be used in machines for

microscrew-cutting from stock in the form of rods of very small diameter.

The embodiments of the invention in which we claim an exclusive property or privilege are defined as follows:

1. A gripping device for resiliently radially clamping an object while allowing axial sliding motion therethrough, including a hollow enclosed cylindrical body having a pair of axially aligned holes forming an inlet and an outlet for the object, a plurality of flexible filaments secured within said body evenly distributed about the longitudinal axis, each being arched at one end so as together to form a bow-net of circular cross section and each having the other end extending axially to form a bundle, a damping mass encircling said bundle comprising a multiplicity of pellets substantially filling said body in compressive contact with said bundle.

2. A gripping device as set forth in claim 1, wherein said pel-

lets define a toroidal configuration.

3. A gripping device as set forth in claim 1, wherein said pellets are made of a hard substance lacking readily deformable properties for effecting damping action through the mutual rubbing of said pellets.

4. A gripping device as set forth in claim 1, wherein said pellets are made of a readily deformable material having high damping power for effecting damping action through combining the intrinsic damping forces of the material with the mutual rubbing of said pellets.

5. A gripping device as set forth in claim 2, wherein said pellets are formed of glass.

6. A gripping device as set forth in claim 3, wherein said pellets are formed of glass.
